UNITED STATES PATENT OFFICE.

HENRY MERLE WILLIAMSON, OF OAK PARK, ILLINOIS.

OSCILLOGRAPH.

Application filed December 31, 1925. Serial No. 78,705.

This invention relates to an X-ray oscillograph which is an improvement on the conventional cathode-ray oscillograph.

An object of this invention is to make a permanent record of an electrical wave having any frequency particularly of waves of high frequency such as the harmonics of the voice.

Other objects will appear in the specification.

This invention is characterized by the use of an anti-cathode incorporated in the conventional cathode-ray oscillograph to create X-rays which are capable of being photographed instantaneously and thus creating a permanent record of any electrical wave passed through the apparatus.

The above mentioned features and other novel features will be more thoroughly understood by referring to the accompanying illustrative drawings and detailed description.

Figure 1 is a partially diagrammatic drawing of an oscillograph constructed in accordance with this invention.

Figure 2 is a partially diagrammatic drawing showing a modification of this invention.

Figures 3 and 4 are illustrative drawings of the photographic record as produced by this invention and one of its modifications, and

Figure 5 is a partially diagrammatic drawing of a further modification of this invention.

Referring more particularly to Figure 1, there is shown an evacuated bulb 1 having a cathode 2 and an anode 3 capable of creating a stream of cathode rays 4 which may be restricted to a narrow stream 5 by means of a shield 6 composed of any substance opaque to cathode-rays. It is necessary to impress a suitable current upon the said cathode and said anode before a cathode-ray stream is established between them. An anti-cathode 7 is placed in the path of the cathode-rays 5 so as to create X-rays at the point of contact 8. A shield 9, composed of any substance capable of retarding X-rays, is placed in any position which is in the path of the X-rays generated by the anti-cathode 7. The shield 9 is provided with a small opening 10 and inasmuch as X-rays travel in a straight line from their source a small stream of X-rays 11, will pass through the opening 10, and fall on a photo-

graphic film 12. Now if means 13 are provided for bending the cathode-ray stream 5, in proportion to any electrical wave which may be impressed upon said bending means 13, the point of contact 8 will vary in proportion to the undulations of said electrical wave. As this point of contact 8 is the source of the X-ray stream 11 passing through the opening 10 in the shield 9, this stream of X-rays 11 will vary in accordance with said source and will travel across the film 12, all in proportion to the said electrical wave. If the film 12 travels by means of the rollers 14 at a constant speed and the X-ray stream 11 varies across the film 12 in proportion to the electrical wave which it is desired to be recorded, it will be readily seen that that portion of the film 12 which is exposed to the action of the X-rays will form a permanent record of the aforementioned electrical wave. It has been found in practice that a secondary shield 15 placed in front of the film 12 and having a hair line opening 16 for the X-ray stream 11 to pass through will greatly increase the clearness and reduce any penumbra of the image obtained on the film 12. The secondary shield 15 must of course be made from some substance which will retard X-rays.

Figure 2 shows this invention in a modified form. In this form the anti-cathode 7' is cylindrical instead of flat as in Figure 1 and instead of the shield 9 as shown in the previous figure, a small granula 17 of lead or other suitable substance is interposed in the path of the X-rays so as to shield a small portion of the film 12 as it travels behind the shield 15, thus leaving a small portion of the film 12 unexposed. Another means for bending the cathode ray 5 is employed in this modification, magnetic means 18 being used instead of electrostatic plates 13 as shown in Figure 1. This is done merely to show that various different forms may be used without departing from the spirit of the invention.

Figure 3 shows a portion of the film 12 passing behind the shield 15. The wave shown is purely diagrammatical. In this case the film appears as it would if produced by the form shown in Figure 1. If the film produced by the form shown in Figure 2 were to be shown, it would be merely a photographic negative of the film illustrated in this figure.

Figure 4 is a portion of the film 25 and the shield 29 as produced by the modification of this invention shown in Figure 5.

Figure 5 shows a modification of this invention which makes it possible to simultaneously record two different electrical waves upon the same film for the purpose of comparison. This feature is used for instance in comparing the primary and secondary windings of an audio frequency transformer. Similar numerals in this figure relate to similar details in Figures 1 and 2. In this modification of the invention, two cathodes 2, 2, and two anodes 3, 3, are provided for the purpose of creating two streams of cathode-rays 5, 5, with separate means 13, 13, for varying said cathode-ray streams, each being independent of the other. A double anti-cathode 19 is provided, the cathode-ray streams 5, 5, striking the said anti-cathode at the points 20 and 21 thus creating two separate sources of X-rays which pass through the openings 22 and 23 in the shield 24 and act upon the photographic film 25 which must be large enough to accommodate the two streams of X-rays 26 and 27. In order that the rays from the two separate sources may not impinge upon each other's part of the film, a shield 28 is necessary. It is found that a secondary shield 29 having hair line slits 30 and 31 for the passage of the X-rays aids in obtaining a clear image.

It is not desired that this invention be limited to any particular form shown except as claimed.

What I claim is:—

1. An oscillograph comprising means for generating X-rays, means for varying said X-rays, and means for recording said variations.
2. An oscillograph comprising means for generating X-rays, means for varying said X-rays in proportion to any electrical wave which may be passed through said varying means, and means for recording said variations.
3. An oscillograph comprising means for generating X-rays, means for varying said X-rays, and means for recording said variations, said recording means being movable.
4. An oscillograph comprising means for generating X-rays, means for varying said X-rays, means for recording said variations, and means for shielding a portion of said X-rays from said recording means.
5. An oscillograph comprising means for generating X-rays, means for varying said X-rays, means for recording said variations, said recording means being movable, and means for shielding a portion of said X-rays from said recording means.
6. An oscillograph comprising means for generating X-rays, means for varying said X-rays, and photographic means for recording said variations.

7. An oscillograph comprising means for generating X-rays, means for varying said X-rays, means for casting a shadow in said X-rays, said shadow varying as said X-rays vary, and means for recording said variations of said shadow.

8. An oscillograph comprising means for generating X-rays, means for varying said X-rays, a shield in the path of said X-rays, said shield having a small opening, a second shield having a hair line opening in line with said variations of said X-rays, and a photographic film adapted to travel behind said second shield.

9. An oscillograph comprising means for generating X-rays, means for varying said X-rays, means for casting a shadow in said X-rays, said shadow varying as said X-rays vary, a shield having a hair line opening extending in a line with the said variations of said shadow, and a photographic film adapted to travel behind said shield.

10. An oscillograph comprising means for generating cathode-rays, means for varying said cathode-rays, and means for instantaneously recording said variations of said cathode-rays permanently.

11. An oscillograph comprising means for generating cathode-rays, means for varying said cathode-rays in proportion to the undulations of any electrical wave which may be impressed upon said varying means, and means for instantaneously recording these variations of said cathode-rays permanently.

12. An oscillograph comprising means for generating cathode-rays, means for varying said cathode-rays, and means for photographing said variations instantaneously.

13. An oscillograph comprising means for generating cathode-rays, means for varying said cathode-rays, an anti-cathode in the path of said cathode-rays forming a source of X-rays, said source varying as said cathode-rays vary, and means for recording said variations of said X-rays.

14. An oscillograph comprising means for generating cathode-rays, means for varying said cathode-rays in proportion to the undulations of any electrical wave impressed upon said varying means, means for converting said cathode-rays into X-rays, said X-rays varying proportionately to said cathode-rays, and means for recording said variations of said X-rays.

15. An oscillograph comprising means for generating cathode-rays, means for varying said cathode-rays, means for converting said cathode-rays into X-rays, said X-rays varying proportionately to said cathode-rays, means for shielding all but a portion of said X-rays, and means for recording the variations of said X-rays not shielded by said shield.

16. An oscillograph comprising a tube containing a cathode and anode, means for

creating cathode-rays between said cathode and anode, means for bending said cathode-rays, an anti-cathode in the path of said cathode-rays, means for casting a shadow in any X-rays generated by the bombardment of said cathode-rays against said anti-cathode, and means for recording any movement of said shadow in said X-rays.

17. An oscillograph comprising a tube containing a cathode and anode, means for creating cathode-rays between said cathode and anode, means for bending said cathode-rays, an anti-cathode in the path of said cathode-rays forming a source of X-rays that vary as the cathode-rays vary, and means for producing a photographic record of such variations.

18. An oscillograph comprising means for creating cathode-rays, electrostatic means for varying said cathode-rays, means for converting said cathode-rays to X-rays, said

X-rays varying proportionately to the variations of said cathode-rays, and means for recording the said variations of said X-rays.

19. An oscillograph comprising an evacuated tube containing a cathode and anode, an anti-cathode, means for bending cathode-rays between said anti-cathode and said cathode, a shield having a small opening placed in the path of any X-rays which might be created at said anti-cathode, a second shield having a hair line opening, said opening being in a line with any variations which might accrue in any X-rays created at said anti-cathode passing through the said small opening in the first mentioned shield, and a photographic means movably mounted behind said second shield.

In testimony whereof I affix my signature.

HENRY MERLE WILLIAMSON.
